Adjustable Scaffold & Form Company, Cleve-
land, Ohio, a corporation

Application October 6, 1932, Serial No. 636,511

12 Claims. (Cl. 187—29)

This invention relates to controlling apparatus and is particularly applicable to controlling of hoists, elevators, or similar devices from one or more remote points.

5 An object of the invention is to provide an improved controlling means which will be simple in operation.

Another object is to provide an improved controlling means by which the operation of a hoist 10 or the like will be rendered extremely safe.

Another object of the invention is to provide an improved controlling device which may be easily installed on or removed from a structure in which a hoist or elevator is to operate.

15 Other objects will hereinafter appear.

The invention will be better understood from the description of one practical embodiment thereof illustrated in the accompanying drawings, in which:

20 Figure 1 is a diagrammatic representation of the controlling means; and

Figure 2 is a somewhat diagrammatic view of the control apparatus associated with a hoist and elevator mechanism.

25 The control apparatus is particularly designed to be used upon a hoist which comprises an engine E, motor, or other source of power arranged to drive a winch W, drum, or reel from which a cable R or other flexible element extends to support a cage or car C and to raise or lower the same. The connection between the source 30 of power and the drum is shown as consisting of two magnetic clutches H and L and there is also provided a magnetic brake B.

35 The driving means may be of any desired type, such as an electric motor, an internal combustion engine, or any other source of power, and if an internal combustion motor or the like is used, the motor itself may be controlled from the same point as is the hoisting operation, by any desired means, one manner in which this may be conveniently done being illustrated in my co-pending application Serial No. 631,529, filed September 2, 1932.

45 The driving unit is connected in any desired manner as by a clutch to a generator 1 having a field 2 controlled by a rheostat 3. Current from this generator passes through conductors 4 and 5 to a terminal board 6 where the conductors are connected to a switch 7.

50 From one side of this switch a conductor 8 passes to a relay 9 being connected to one end of the coil of this relay, as well as to one of its contacts. From the other contact of the relay 55 a conductor 10 passes to a resistance 11 and

thence conductor 12 is connected to one end of the coil 13 of a magnetic brake which controls the rotation of the hoisting drum.

From the other end of the coil of the brake, a conductor 14 is connected to one end of coils of magnetic clutches 15 and 16, the former being adapted to rotate the drum in a direction for hoisting, and the latter in a direction for lowering. From the other end of the coil 15 (of the hoisting clutch), a conductor 17 leads to one contact of a relay 18 and from the free end of the coil 16 (of the lowering clutch), a conductor 19 passes to one contact of a relay 20. A conductor 21 extends from the side of the switch connected to conductor 5 to the remaining contacts of relays 18 and 20.

It will thus be seen that when relay 9 is closed, current may pass from the generator through coil 13 to release the brake and thence to either of the coils 15 or 16, to control the clutches by which the hoisting or lowering operation is performed, and these clutches may be selectively engaged by the operation of relays 18 and 20. Preferably the relays are mechanically interlocked so that it will be impossible to engage both clutches at the same time.

Means for operating the relays are positioned upon a control panel 22 which may be positioned at any convenient point and remote from the location of the relays themselves. Upon this panel is mounted a switch 23 for controlling the hoisting relay 18, a switch 24 for controlling the lowering relay 20, a switch 25 for stopping the operation of the hoist in either raising or lowering, and a plurality of switches 26, which automatically determine the floor or elevation at which the cage shall stop. Pilot lights 27 and 28 are also positioned upon the board to indicate when and in which direction the hoist is moving.

Connected to conductor 21 is a conductor 29 which passes through a thermostatic switch 30, and thence through switches 31, one of which is positioned at each floor or station at which the hoist should stop, and which are closed only when the doors at these stations are closed, and are opened by the opening of the doors, to a series of switches 32, conductor 29 being connected to one side of each of these switches.

One of these switches 32 is positioned adjacent each floor or station and arranged to be mechanically opened by the cage when it reaches this station, as by having an arm engaged by a projection upon the cage. Each floor stop switch 32 is connected by a conductor 33 to a switch 26, 55

and the switches 26 are all connected by a conductor 34 to one side of switch 25.

This switch is of a type which remains closed unless it is being held opened by the hand of the operator, so that current may at all times pass through it to a conductor 35 which is connected to one side of each of the switches 23 and 24. These two switches are of a type which remains closed only when manually held, the current at other times passing through interlock switches to be hereinafter described.

The thermostatic switch 30 is like, and may be used in place of, the thermostatic switch shown in my above mentioned copending application.

Like that switch, it is intended to be positioned adjacent or in the cooling system of the engine, when an internal combustion engine is used to drive the apparatus, so that the hoisting apparatus cannot be used until the engine has become sufficiently warmed up. In the former case, the thermostatic switch was in the circuit which controlled the operation of the mechanical clutch between the source of power and the hoist, while in this instance it controls the circuit of magnetic clutches.

From the remaining side of switch 23 a conductor 36 passes to one end of the magnetic coil of relay 18, and from the other end of this coil a conductor 37 returns to the board 22. From the last mentioned conductor, a conductor 38 passes to a switch 39 which is the top limit switch of the hoist or elevator, and is positioned to be opened by the cage when this reaches the upper limit of its travel.

From this switch a conductor 40 returns to the end of the magnetic coil 9 opposite its connection with conductor 8.

Hence, when switch 23 is closed, current may pass from the generator through conductors 21, 40 29, switch 30, switches 31, one of the switches 32, one conductor 33, one of the switches 26, conductor 34, switch 25, conductor 35, switch 23, conductor 36, relay 18, conductor 37, conductor 38, switch 39, conductor 40, relay 9, and conductor 8; 45 back to the generator, operating relays 18 and 9 to release the brake and engage the hoisting clutch.

The pilot light 27 is shunted across between the conductors 36 and 37, so that this light will be 50 illuminated whenever the hoist is raising its load.

Similarly a conductor 41 passes from switch 24 to one end of the magnetic coil of relay 20, and a conductor 42 extends from the other end of this relay coil to a switch 43 adapted to be 55 opened when the cage is at its lowermost position and constituting the bottom limit switch. The other side of switch 43 is connected to conductor 40.

Hence, when switch 24 is closed, current will 60 pass from the generator through conductor 21, conductor 29, switch 30, switches 31, one of the switches 32, one of the conductors 33, one of the switches 26, conductor 34, switch 25, conductor 35, switch 24, conductor 41, relay 20, conductor 42, 65 switch 43, conductor 40, relay 9, and conductor 8; back to the generator, operating relays 9 and 20 to release the brake and to engage the lowering clutch.

Pilot light 28 is shunted across conductors 41 and 42 to indicate when the hoist is lowering.

Upon the board 6 are positioned a hoist interlock switch 44 and a lowering interlock switch 45, one side of each of these being connected to one 75 end of the coils of relays 18 and 20, respectively.

The other ends of the switches are connected together and to conductor 35 by a conductor 46, so that switches 44 and 45 are in parallel with switches 23 and 24, respectively, and so close when their respective manual switches 23 or 24 are closed and remain closed to maintain the circuits closed after they have been momentarily closed by switches 23 and 24 until the circuits are opened, as by switch 25, 32, 39, or 43. These switches 44 and 45 are of conventional hold-in type which are moved to closed position electro-magnetically when the circuits with which they are in parallel are closed.

A third series of control switches is mounted upon a portable panel 47 and consists of a hoisting switch 48, a lowering switch 49, and a stop switch 50, corresponding to switches 23, 24 and 25, respectively. One side of each of these switches is connected to conductor 46. The other side of the switch 48 is connected to a conductor 51, which, in turn, is connected to a conductor 36. The other side of switch 49 is connected by conductor 52 to conductor 41. The other side of switch 50 is connected by conductor 53 to conductor 29, so that it will be seen that when the switch 50 remains closed, the closing of switch 48 will permit current to flow through conductors 21, 29, 53, switch 50, conductor 46, switch 48, conductor 51, relay 18, conductor 31, conductor 38, switch 39, conductor 40, relay 9, conductor 8; back to the generator, operating the hoisting and brake relays much in the manner in which their operation was first described, but cutting out the circuit of switches 30, 31 and 32.

Similarly, if switch 49 is actuated, the lowering relay 20 will be operated and the clutch released.

The panel 47 may be positioned at any convenient point, being merely connected to the other apparatus by four conductors which, for facility in installing, may be separable and a pronged plug or like connection 54 inserted in them, one part being upon some stationary part of the mechanism where it can be easily reached. Likewise, conductors 38, 40 and 42 are conveniently detachably plugged together by a plug 55.

The door safety switches 31, and floor switches 32 are conveniently mounted on a flexible conduit which may be easily placed in operating position, and if desired, conveniently detachably connected to the board 22. By this means, the controls may be easily installed and moved from place to place without the necessity for any permanent electrical connections being made upon the job, rendering the device particularly suitable for hoists used in building operations and the like, where its installation is temporary.

It will be obvious that when the control panel 47 is used, all switches 26 must be open, and conversely that when the switches on panel 22 are in use, it will be necessary to disconnect panel 47 by separating the parts of plug 54. Otherwise switches 25 and 50 would be in parallel with each other, and when either of them were opened the current would pass through the other and the hoist would continue in its motion instead of being stopped. As the switches on panels 22 and 47 are connected in parallel with each other at the entrance of their conductors to panel 6, it will be apparent that switches 48, 49 and 50 will effect the elements on panel 6 exactly as would switches 23, 24, and 25, respectively, and that the actuation of the relays and the like will be precisely the same, excepting for the fact that the circuit will not be automatically broken by switches 31 and 32.

Inasmuch as the panel 47 is not intended for general use, but is used by an operator when he wishes absolute control of the car independently of the means for automatically determining the position in which it stops, it is apparent that the connecting of switches 48 to 50 into the circuits of switches 23 to 25 between switches 31 and 32 and the relays gives him such a control. This control is unaffected by the setting of switches 31 and 32, so that he may cause the car to stop between points at which the floor switches have been installed, and may operate it even when the doors are open. Such operation may be desirable at times, although, of course, the normal operation is through switchboard 22.

Obviously when switchboard 47 is in use, the circuits can be broken only by the actuation of switch 50 and no automatic provision for stopping the hoist is effective. For instance if switch 48 be closed, current may pass from generator 1 through conductors 4, 8, 9, 40, switch 39, conductor 38, conductor 37 to relay 18, thence through conductor 51 to switch 48, through this switch downwardly through conductor 46 to switch 50, through this switch and then through conductors 53, 21 and 5 back to the generator. As soon as this current has started to flow, switch 44 is closed so that release of switch 48 allows the current to reach conductor 46 through switch 44. Irrespective as to whether switch 44 or 48 or both are closed, the circuit will be broken by pressing switch 50.

The above described embodiment of the invention is applied to a hoist, but it will be apparent that the control could well be applied to other moving apparatus such, for instance, as a crane, car or the like, and that when applied to something moving in a horizontal direction instead of vertical direction, the clutches will operate to move the device forwardly or rearwardly instead of up or down.

While I have described the illustrated embodiment of my invention in some particularity, obviously many others will readily occur to those skilled in this art, and I therefore do not limit myself to the precise details shown and described herein, but claim as my invention all embodiments, modifications and variations coming within the scope of the appended claims.

50 I claim:

1. A control apparatus for object moving means including a source of power constantly operating in one direction, a power transmitting device, means for connecting said transmitting device to said source of power to operate it in either of two directions, and a brake, said control comprising electromagnetic means operatively associated with the connecting means for moving the object in one direction, electromagnetic means operatively associated with the connecting means for moving the object in the other direction, and electromagnetic means associated with said brake, a circuit including said first mentioned electromagnetic means, a circuit including said second mentioned electromagnetic means, said circuits having portions in common including said third mentioned electromagnetic means, a normally open switch in the separate portion of said first mentioned circuit, a switch 70 in said portion of said circuits adapted to be opened by the object on reaching the predetermined position, a normally open switch in the separate portion of said second mentioned circuit, a switch in said portion of said circuit adapted 75 to be opened by the object on reaching the pre-

determined position, a switch in the common portion of said circuits, and means normally maintaining the last mentioned switch closed.

2. A control for object moving apparatus which includes a source of power arranged to rotate continuously in one direction, power transmitting means connected to the object, connecting means between said source of power and power transmitting means for operating said power transmitting means in one direction, connecting means between said source of power and power transmitting means for operating said power transmitting means in another direction, and means preventing motion of said power transmitting means, which comprises electromagnetic means controlling said first mentioned connecting means, electromagnetic means controlling said second mentioned connecting means, and electromagnetic means controlling said motion preventing means, a relay controlling said first mentioned electromagnetic means, a second relay controlling said second mentioned electromagnetic means, a third relay controlling said third mentioned electromagnetic means, connections between said two first mentioned relays and the third mentioned relay, a circuit including said first and third mentioned relays and said connection, a manually operable switch in said circuit, means normally holding said switch open, a hold-in switch in parallel with said manually operable switch, a second circuit including said second and third mentioned relays and said first mentioned connection, a manually operable switch in said second circuit, means normally holding said switch open, and a hold-in switch in parallel with said last mentioned switch.

3. A control for object moving apparatus which includes a source of power arranged to rotate continuously in one direction, power transmitting means connected to the object, connecting means between said source of power and power transmitting means for operating said power transmitting means in one direction, connecting means between said source of power and power transmitting means for operating said power transmitting means in another direction, and means preventing motion of said power transmitting means, which comprises electromagnetic means controlling said first mentioned connecting means, electromagnetic means controlling said second mentioned connecting means, and electromagnetic means controlling said motion preventing means, a relay controlling said first mentioned electromagnetic means, a second relay controlling said second mentioned electromagnetic means, a third relay controlling said third mentioned electromagnetic means, connections between said two first mentioned relays and the third mentioned relay, a circuit including said first and third mentioned relays and said connection, a manually operable switch in said circuit, means normally holding said switch open, a hold-in switch in parallel with said manually operable switch, a second circuit including said second and third mentioned relays and said first mentioned connection, a manually operable switch in said second circuit, means normally holding said switch open, and a hold-in switch in parallel with said last mentioned switch, said circuits having a portion in common, a manually operable switch in said common portion of said circuits, and means normally maintaining said switch closed.

4. A control for object moving apparatus which includes a source of power arranged to rotate

- continuously in one direction, power transmitting means connected to the object, connecting means between said source of power and power transmitting means for operating said power transmitting means in one direction, connecting means between said source of power and power transmitting means for operating said power transmitting means in another direction, and means preventing motion of said power transmitting means,
- 10 which comprises electromagnetic means controlling said first mentioned connecting means, electromagnetic means controlling said second mentioned connecting means, and electromagnetic means controlling said motion preventing means,
- 15 a relay controlling said first mentioned electromagnetic means, a second relay controlling said second mentioned electromagnetic means, a third relay controlling said third mentioned electromagnetic means, connections between said two first mentioned relays and the third mentioned relay, a circuit including said first and third mentioned relays and said connection, a manually operable switch in said circuit, means normally holding said switch open, a hold-in switch
- 20 in parallel with said manually operable switch, a second circuit including said second and third mentioned relays and said first mentioned connection, a manually operable switch in said second circuit, means normally holding said switch open, and a hold-in switch in parallel with said last mentioned switch, said circuits having a portion in common, a manually operable switch in said common portion of said circuits, means normally maintaining said switch closed, a plurality
- 25 of object controlled switches arranged in parallel in said common portion of the circuits, and manually operable switches for connecting any of said plurality of switches into the common portion of said circuit.
- 30 5. A control for object moving apparatus which includes a source of power arranged to rotate continuously in one direction, power transmitting means connected to the object, connecting means between said source of power and power transmitting means for operating said power transmitting means in one direction, connecting means between said source of power and power transmitting means for operating said power transmitting means in another direction, and means preventing motion of said power transmitting means,
- 35 which comprises electromagnetic means controlling said first mentioned connecting means, electromagnetic means controlling said second mentioned connecting means, and electromagnetic means controlling said motion preventing means,
- 40 a relay controlling said first mentioned electromagnetic means, a second relay controlling said second mentioned electromagnetic means, a third relay controlling said third mentioned electromagnetic means, connections between said two first mentioned relays and the third mentioned relay, a circuit including said first and third mentioned relays and said connection, a manually operable switch in said circuit, means normally holding said switch open, a hold-in switch in parallel with said last mentioned switch, said circuits having a portion in common, a manually operable switch in said common portion of said circuits, means normally maintaining said switch closed, a plurality
- 45 of object controlled switches arranged in parallel in said common portion of the circuits, and manually operable switches for connecting any of said plurality of switches into the common portion of said circuit.
- 50 6. A control for object moving apparatus which includes a source of power arranged to rotate continuously in one direction, power transmitting means connected to the object, connecting means between said source of power and power transmitting means for operating said power transmitting means in one direction, connecting means between said source of power and power transmitting means for operating said power transmitting means in another direction, and means preventing motion of said power transmitting means,
- 55 which comprises electromagnetic means controlling said first mentioned connecting means, electromagnetic means controlling said second mentioned connecting means, and electromagnetic means controlling said motion preventing means,
- 60 a relay controlling said first mentioned electromagnetic means, a second relay controlling said second mentioned electromagnetic means, a third relay controlling said third mentioned electromagnetic means, connections between said two first mentioned relays and the third mentioned relay, a circuit including said first and third mentioned relays and said connection, a manually operable switch in said circuit, means normally holding said switch open, a hold-in switch in parallel with said last mentioned switch, said circuits having a portion in common, a manually operable switch in said common portion of said circuits, means normally maintaining said switch closed, a plurality
- 65 of object controlled switches arranged in parallel in said common portion of the circuits, and manually operable switches for connecting any of said plurality of switches into the common portion of said circuit.
- 70 7. Control apparatus for an object moving device including a source of power constantly operating in one direction, a power transmitting means, an engaging means for connecting the source of power to the power transmitting means to move the object in one direction, a second engaging means for connecting the source of power to the power transmitting means to move the object in another direction, and a brake preventing motion of the power transmitting means,
- 75 which comprises a plurality of electromagnetic means controlling said engaging means and brake, a circuit comprising a common portion connected to each of said electromagnetic means associated with the engaging means and the braking means, whereby the braking means is rendered inoperative by the flow of current through the common part of said circuit, a switch in the separate part of said circuit normally in open position and adapted to be closed manually, a switch in the common portion of said circuit normally closed and adapted to be opened manually, a circuit closing device in parallel with each of said first mentioned switches and adapted to close said circuit when said switches are actuated and to maintain said circuits closed until broken elsewhere, and a switch

of object controlled switches arranged in parallel in said common portion of the circuits, manually operable switches for connecting any of said plurality of switches into the common portion of said circuit, a manually operable switch arranged in parallel with the first mentioned circuit, means normally maintaining said switch open, a manually operable switch connected in parallel with the second mentioned circuit, means normally maintaining said switch open, a manually operable switch connected in parallel to the common portion of said circuit, means normally holding said switch closed, said three last mentioned switches being connected into the circuits between the object operated switches and the relays.

8. Control apparatus for an object moving device including a source of power constantly operating in one direction, a power transmitting means, engaging means for connecting the source of power to the power transmitting means to move the object in one direction, a second engaging means for connecting the source of power to the power transmitting means to move the object in another direction, and a brake preventing motion of the power transmitting means, which comprises three electromagnetic means controlling said engaging means and brake, circuits including the electromagnetic means associated with the engaging means and having a common portion including the electromagnetic means associated with the brake, whereby the brake is rendered inoperative by the flow of current through either circuit, a manually closable switch in the separate part of each circuit, means normally holding said switches in open position, a manually operable switch in the common portion of said circuits, means normally holding said switch closed, an electrically operated circuit closing device in parallel with each of said first mentioned switches adapted to close said circuits when said switches are actuated and to maintain said circuits closed until broken elsewhere, a plurality of switches adapted to be opened by said object when it reaches predetermined positions, and a plurality of manually operable switches for connecting any of said switches selectively into the common portion of said circuits.

9. Control apparatus for an object moving device including a source of power constantly operating in one direction, a power transmitting means, an engaging means for connecting the source of power to the power transmitting means to move the object in one direction, a second engaging means for connecting the source of power to the power transmitting means to move the object in another direction, and a brake preventing motion of the power transmitting means, which comprises a plurality of electromagnetic means controlling said engaging means and brake, a circuit comprising a common portion connected to each of said electromagnetic means associated with the engaging means and the braking means, whereby the braking means is rendered inoperative by the flow of current through the common part of said circuit, a switch in the separate part of said circuit normally in open position and adapted to be closed manually, a switch in the common portion of said circuit normally closed and adapted to be opened manually, a circuit closing device in parallel with each of said first mentioned switches and adapted to close said circuit when said switches are actuated and to maintain said circuits closed until broken elsewhere, and a switch

in the separate portion of each circuit adapted to be opened by the object when it reaches an extreme position.

8. Control apparatus for an object moving device including a source of power constantly operating in one direction, a power transmitting means, an engaging means for connecting the source of power to the power transmitting means to move the object in one direction, a second engaging means for connecting the source of power to the power transmitting means to move the object in another direction, and a brake preventing motion of the power transmitting means, which comprises a plurality of electromagnetic means controlling said engaging means and brake, a circuit comprising a common portion connected to each of said electromagnetic means associated with the engaging means and the braking means, whereby the braking means is rendered inoperative by the flow of current through the common part of said circuit, a switch in the separate part of each circuit normally in open position and adapted to be closed manually, a switch in the common portion of said circuit normally closed and adapted to be opened manually, a circuit closing device in parallel with each of said first mentioned switches and adapted to close said circuit when said switches are actuated and to maintain said circuits closed until broken elsewhere, and a series of switches connected in series actuated by devices along the path of the object.

9. A control for object moving apparatus which includes a source of power constantly operating in one direction, power transmitting means, a clutch between said source of power and power transmitting means, and a brake associated with said power transmitting means, said control comprising electromagnetic means operatively connected with said clutch, electromagnetic means operatively connected to said brake, a circuit including a relay arranged to engage the clutch and simultaneously disengage the brake, a manually operable switch in said circuit, resilient means normally maintaining the switch open, an automatic hold-in switch in parallel with said manually operable switch and arranged to close the circuit when the manually operable switch is closed and to remain closed until the circuit is broken elsewhere, and a manually operable switch in said circuit and arranged to break the circuit, and resilient means normally holding said last mentioned switch in closed position.

10. A control for object moving apparatus which includes a source of power constantly operating in one direction, power transmitting means, a clutch between said source of power and power transmitting means, and a brake associated with said power transmitting means, said control comprising electromagnetic means operatively connected with said clutch, electromagnetic means operatively connected to said brake, a circuit including a relay arranged to engage the clutch and simultaneously disengage the brake, a manually operable switch in said circuit, resilient means normally maintaining the switch open, an automatic hold-in switch in parallel with said manually operable switch and arranged to close the circuit when the manually operable switch is closed and to remain closed until the circuit is broken elsewhere, and a man-

ually operable switch in said circuit and arranged to break the circuit, and resilient means normally holding said last mentioned switch in closed position, a plurality of switches arranged to be actuated by the object on reaching any one of a plurality of predetermined positions, and selective connecting means whereby any one of said plurality of switches may be connected in series with said circuit.

11. A hoist comprising a car, a winch, a cable passing from said winch to raise or lower the car, a source of power adapted to drive said winch, two clutches arranged to connect said source of power to said winch to drive it in either of two directions, a brake connected to said winch, electromagnetic means controlling the first mentioned clutch, electromagnetic means controlling the second mentioned clutch, electromagnetic means controlling said brake, a generator driven by said source of power, a relay arranged to connect said generator to said first mentioned electromagnetic means, a second relay arranged to connect said generator to said second mentioned electromagnetic means, a third relay arranged to connect said generator to said third mentioned electromagnetic means, a connection common to said relays, two circuits, one including said first mentioned relay and the other including the second mentioned relay, the circuits having common portions one of which includes the third mentioned relay, a manually operable switch in the common portion of said circuits, resilient means normally maintaining said switch closed, a manually operable switch in the separate portion of the first mentioned circuit, resilient means normally maintaining said switch open, a manually operable switch in the separate portion of the second mentioned circuit, resilient means maintaining said switch open, a limit switch in the separate portion of said first mentioned circuit and arranged to be operated by the car at one limit of its travel, a limit switch in the separate portion of the second mentioned circuit and arranged to be opened by said car at the other limit of its travel, a plurality of switches arranged to be opened by the car in the common portion of said circuits, a plurality of manually operable switches, each connected in series with one of said last mentioned switches and adapted to connect said car operated switches selectively into the common portion of said circuit.

12. A control for apparatus arranged to move an object, which apparatus includes a source of power, means for rendering the source inoperative to move the object and to render the source operative to move the object, which comprises electromagnetic means selectively controlling said above mentioned means, a circuit controlling said electromagnetic means, a switch in said circuit for closing the same, a plurality of circuits each adapted to move the object in a given direction, a switch in each of said circuits controlling the same, a portion of each of said circuits being common, a plurality of switches adapted to be opened by the object upon reaching any one of a plurality of predetermined positions, means for connecting any of said switches selectively into said common portion of the circuit, and a thermally controlled switch in the common portion of said circuit.
